UNITED STATES PATENT OFFICE.

KIRKLEY HYDE, OF LOWELL, MASSACHUSETTS, ASSIGNOR OF THREE-FOURTHS TO JAMES W. BENNETT, ALBERT M. MOORE, AND FREDERICK TAYLOR, ALL OF SAME PLACE.

WOOD-RIM PULLEY.

SPECIFICATION forming part of Letters Patent No. 309,145, dated December 9, 1884.

Application filed May 12, 1884. (No model.)

To all whom it may concern:

Be it known that I, KIRKLEY HYDE, a citizen of the United States, residing at Lowell, in the county of Middlesex and Commonwealth of Massachusetts, have invented certain new and useful Improvements in Wood-Rim Pulleys, of which the following is a specification.

My invention relates to wood-rim pulleys; and it consists in the combinations hereinafter 10 described and claimed.

In the accompanying drawings, Figure 1 is a side elevation of a pulley constructed according to my invention, a part of the outer fellies thereof being broken away to show the 15 outer end of one of the arms, the screw, the wedges, and nuts, and the ends of the foundation-fellies; Fig. 2, an enlarged side elevation of the outer portion of one of the spider-arms and the adjacent foundation-fellies, the outer 20 end of the arm, the nut, check-nut, and wedges being in central section on a plane perpendicular to the axis of the pulley.

A is a metallic spider, consisting of a hub, *a*, and arms *a'*, preferably of cast metal, of any 25 usual construction except as to the outer ends of the arms, each of which is provided with a radial screw, *B*, cast or otherwise secured from turning in the outer ends of the arms *a'*.

On each screw *B*, beyond the arm, are, in 30 the order named below, a check-nut, *b'*, another nut, *b*, both turning on said screw *B*, a truncated wedge, *C*, provided with a central opening, *c*, large enough to allow the screw to pass freely through it, and another truncated 35 wedge, *D*, having a threaded central opening which engages with said screw *B*. The base of the outer wedge is nearest the face of the pulley. The base of the inner wedge is nearest the end of the arm, the base of the last-named

wedge being an imaginary plane at right angles to the screw at the widest part of said wedge, the material added to the wedge between its base and the end of the arm being for strength merely, and being added because the thinner or outer end of the truncated 45 wedge is hollowed out to receive the thin end of the wedge. The ends of the middle or foundation fellies are each cut to fit over the outer wedge and between the inclined faces of the wedges. The fellies *F* are placed in position 50 when the nuts are loosened or turned toward the ends of the arms, and the inner wedge is then forced outward by turning the nut against it, thereby causing the end of the felly to be pinched between the wedges, and, owing to the 55 inclination of the contiguous surfaces of the felly and wedges, causing the felly to be crowded endwise toward the arm next adjacent and preventing any endwise or other motion. It will be understood that all the foundation 60 fellies are put in place before any of the nuts are turned up. To the foundation fellies are attached the outer fellies by screws, or nails, or brads, and glue, and the rim is finally turned 65 true in the usual manner.

I claim as my invention—

The combination of the metallic spider having arms, each provided with a radial screw, the outer wedges having internal screw-threads to engage with said screws, the inner wedges 70 having openings to receive said screws, and the nuts, and the foundation fellies having wedge-shaped ends, as and for the purpose specified.

KIRKLEY HYDE.
